UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

PUMPING APPARATUS.

1,211,408.

Specification of Letters Patent.

Patented Jan. 9, 1917.

Application filed February 3, 1912. Serial No. 675,324.

To all whom it may concern:

Be it known that I, MATTHEW T. CHAPMAN, a citizen of the United States, residing at Aurora, in the county of Kane, State of Illinois, have invented certain new and useful Improvements in Pumping Apparatus, of which the following is a specification, reference being had to the accompanying drawings.

10 My invention relates to mechanism for reciprocating the pump rod or rods of a single or double acting deep well pump.

It has for its objects to provide improved operating mechanism by which the pump rod or rods are given a long stroke which is substantially uniform from one end of the stroke to the other, as distinguished from the action of a crank in which the speed of the stroke varies more or less throughout the 20 entire stroke; and also to provide improved means for converting the rotary movement of an endless driving device into the reciprocating movement necessary for actuating the pump rod or rods; also to provide certain other improvements, which will be hereinafter pointed out. I accomplish these objects as illustrated in the drawings and as hereinafter described.

What I regard as new is set forth in the 30 claims.

In the accompanying drawings, Figure 1 is a side view of my improved mechanism; Fig. 2 is a front view; Fig. 3 is a horizontal section on line 3—3 of Fig. 1; Fig. 4 is a 35 plan view, partly broken away; and Fig. 5 is a horizontal section on line 5—5 of Fig. 1.

My improved pumping mechanism comprises an endless driving device consisting of a chain or chains arranged to travel in a 40 vertical plane adjacent to the pump rod or rods, such endless driving device being driven continuously in the same direction and being connected with the pump rod or rods so that the continuous movement of the 45 endless driving mechanism effects the reciprocation of the pumping devices. Provision is made for driving the chain or chains either from an engine or motor, or by a windmill or other equivalent device; for adjusting the chain or chains to compensate 50 for wear, and for moving aside the operating mechanism to permit the pump-rod to be removed.

Referring to the drawings, 6 indicates a 55 base-plate of suitable construction to sup-

port a standard 7 which rises therefrom and is provided with a laterally-projecting arm 8 at its upper end.

9 indicates a rod or bar, the lower end of which is secured to the base-plate 6, preferably by nuts 10—11, its upper end passing through the outer end portion of the arm 8 and being secured in place by nuts 12—13 above and below said arm, as shown in Fig. 1. The rod 9 serves to brace the arm 8 and prevent the standard 7 from tilting. By adjusting the nuts 12—13 upon the rod 9 it may be kept under the proper tension to prevent sagging of the arm 8.

As shown in Figs. 1 and 5, the standard 7 is provided at its inner edge with a flange 14 which extends longitudinally thereof and is planed or made smooth so as to form a way or guide for a head 15 which embraces the same and travels thereon, as best shown 75 in Figs. 1 and 5. The head 15 is connected by a web 16 with a block 17, to which is secured the upper end of the pump-rod 18, preferably by nuts 19—20, as shown in Fig. 1. Thus, as the pump-rod 18 reciprocates, 80 the head 15 will slide up and down on the way 14. 21 indicates a crank-arm, which is pivoted to the upper portion of the block 17 by a pivot 22, as shown in Fig. 1. The purpose of this crank-arm will be herein- 85 after set forth. 23—24 indicate two U-shaped frames which are mounted upon the base 6 at opposite sides of the pump-rod 18 and of the standard 7, as best shown in Fig. 2. 25—26 indicate shafts mounted upon 90 the frames 23—24, respectively, and carrying gears 27—28 and sprocket-wheels 29—30, respectively, said sprocket-wheels being placed at the inner ends of said shafts, as shown in Fig. 2. 31 indicates a shaft 95 which is mounted in the frames 23—24 and is arranged parallel with the shafts 25—26. Said shaft carries two pinions 32, one of which is shown in Fig. 1, which pinions mesh with the gears 27—28 for driving the same. The shaft 31 is also provided with fast and loose pulleys 33—34, as shown in Fig. 1.

As best shown in Fig. 4, the arm 8 of the standard 7 is provided with a socket 35 to receive the shank 36 of a frame or head 37 which depends from the arm 8, being supported by bolts 38, as shown in Figs. 1 and 2. The bolts 38 pass through the arm 8 and are provided at their upper ends with nuts 39 110

so that by adjusting the position of said nuts the frame 37 may be moved up to compensate for wear and keep the chains hereinafter mentioned taut. As shown in Fig. 2, the frame 37 is provided with depending arms or brackets 40 at opposite sides of the standard 7, which arms are provided with bearings 41 which support shafts 42-43, said shafts carrying sprocket-wheels 44-45 arranged over and in line with the sprocket-wheels 29-30, respectively. Said shafts also carry ratchet-wheels 46-47, as shown in Figs. 1 and 2. 48-49 indicate chains which work on and are driven by the sprocket-wheels 29-44 and 30-45, as shown in Fig. 2. As best shown in Fig. 1, the crank-arm 21 is connected with the chains 48-49 by a pin 50 which serves also as a pivot to unite the adjoining links of the chains. It will be apparent that by this construction, when the shaft 31 is driven, the gears 27-28 will rotate and consequently drive the chains 48-49. The movement of the chains, through the connection of the crank-arm 21 therewith, will consequently reciprocate the pump rod or rods. It will be apparent also that during the greater part of the movement of the pump-rod, either up or down, it will move at a uniform rate, the rate varying only as the crank-arm slows down in passing around either the upper or the lower sprocket-wheels. The upper end of the pump-rod is held steady by means of the sliding block 15, but the crank-arm 21, of course, swings upon its pivot 22 as it passes around the upper or lower sprocket-wheels. In order to provide for operating the pump-rod by a windmill, or other equivalent device, I provide a forked lever 51, the arms of which are pivoted upon the shafts 42-43, said arms being provided with pawls 52 which engage the ratchet-wheels 46-47, as shown in Fig. 1, so that by swinging the lever 51 the chains may be driven. 53 indicates a pitman connecting the lever 51 with the windmill. It will be understood, of course, that when the lever 51 is employed for driving the chains the shaft 31 is not to be driven by the pulley 33, the driving belt being then on the loose pulley 34. If a motor is employed for driving the shaft 31 through the medium of the pulley 33, the windmill will preferably be disconnected or thrown out of operation. In order to hold the ratchet-wheels 46-47 against reverse movement when the lever 51 is employed for driving them, I provide detents 54, as shown in Figs. 1 and 2. 55 indicates the upper end of a well-tube and 56 the discharge outlet therefrom, but this forms no part of my present invention.

As best shown in Fig. 3, the standard 7 and the U-shaped frames 23-24 are slidably mounted on the base so that they may be moved away from over the well to permit of

the removal of the pump-rod when necessary. When the standard and frames are in operative position, they are held in place by the rod 9, but such rod may be disconnected from the base by loosening or removing the nuts 10-11 and the nuts 12-13. If, then, the pump-rod is disconnected from the driving chains by removing the pivot pin 50, the standard and frames, with the parts carried by them, may be slid to one side, leaving the pump-rod exposed so that it may readily be removed.

That which I claim as my invention, and desire to secure by Letters Patent, is,—

1. A pumping mechanism, comprising a standard having a horizontal arm, a bracket adjustably supported by said arm, a sprocket-wheel carried by said bracket, a lower sprocket-wheel, an endless chain operating on said sprocket-wheels, means for driving said chain, a pump-rod, and swinging means connecting said pump-rod with said chain.

2. A pumping mechanism, comprising a standard having a horizontal arm, a bracket adjustably supported by said arm, sprocket-wheels carried by said bracket, lower sprocket-wheels, endless chains operating on said sprocket-wheels, a pump-rod extending between said chains, a swinging connection connecting said pump-rod with said chains, and means for driving said chains.

3. A pumping mechanism, comprising a base, a standard, upper sprocket-wheels supported by said standard, frames mounted on said base, sprocket-wheels supported by said frames, endless chains operating on said sprocket-wheels, a pump-rod extending between said chains, a swinging connection between said pump-rod and said chains, and means for driving said chains, said standard and brackets being slidably mounted on the base whereby they may be moved away from the pump-rod.

4. A pumping mechanism, comprising a base, a standard, upper sprocket-wheels supported by said standard, frames mounted on said base, sprocket-wheels supported by said frames, endless chains operating on said sprocket-wheels, a pump-rod extending between said chains, a swinging connection between said pump-rod and said chains, means for driving said chains, said standard and brackets being slidably mounted on the base whereby they may be moved away from the pump-rod, and a rod connecting the upper portion of the standard with the base.

5. In a pumping mechanism, the combination of a frame, a head slidably mounted thereon, a pair of endless chains supported at one end by said head and at the other end by said frame, a plurality of bolts adjustably connecting said head with said frame for tightening said chains, means for driving said chains in unison, a pump-rod, and connections between said chains and said

pump-rod whereby the movement of the chains reciprocates the pump-rod.

6. In a pumping mechanism, the combination of a frame, a head comprising a shank 5 slidably mounted in a suitable slideway at the upper end of said frame, a pair of endless chains supported at one end by said head and at the other end by said frame below said head, a plurality of bolts adjustably connecting said head with said frame for tightening said chains, means for driving said chains in unison, a pump-rod, and connections between said chains and said pump-rod whereby a movement of the chains 10 reciprocates the pump-rod.

7. In a pumping mechanism, the combination of a frame comprising a vertically-extending guide-plate and a horizontally-ex-

tending arm, a head comprising a shank slidably mounted in a suitable slideway in said arm, a pair of endless chains supported at one end by said head and at the other end by said frame below said head, a plurality of bolts adjustably connecting said head with said frame for tightening said chains, a 20 slide-block embracing said guide-plate and adapted to be reciprocated therealong, a pump-rod having fixed connection with said slide-block, means for driving said chains in unison, and a link pivotally connected 25 with said slide-block and with said chains.
